COMBINATION REEL AND CONTAINER

William J. Wilke, Baltimore, Md.

Application March 15, 1956, Serial No. 40,623

Term of patent 14 years

(Cl. D41—1)

Fig. 2.

Fig. 1 is a side elevational view of a combination reel and container, showing my new design, said container being shown in an open position;

Fig. 2 is a top view of the design shown in Fig. 1;

Fig. 3 is a side elevational view similar to Fig. 1, showing the combination reel and container in a closed position; and

Fig. 4 is a top view of the design illustrated in Fig. 3.

The dominant features of the design reside in the portions shown in full lines.

I claim:

The ornamental design for a combination reel and container, as shown and described.
